UNITED STATES PATENT OFFICE.

MARTIN JAMES CURTIS, OF BILLINGS, MONTANA.

MINER'S LAMP.

976,785.

Specification of Letters Patent. Patented Nov. 22, 1910.

Application filed April 23, 1910. Serial No. 557,195.

To all whom it may concern:

Be it known that I, MARTIN JAMES CURTIS, a citizen of the United States, residing at Billings, in the county of Yellowstone 5 and State of Montana, have invented certain new and useful Improvements in Miners' Lamps, of which the following is a specification.

This invention relates to miners' lamps 10 and has for an object to provide an efficient lamp of this character, constructed to operate as an ordinary acetylene lamp.

Another object of the invention is to provide an efficient acetylene lamp, which shall 15 be simple in construction, thereby allowing the same to be constructed of a small number of parts, so that the same may be readily adapted as a miner's lamp.

A further object is to provide a novel arrangement of parts forming the generating vessel and novel means for supporting a lamp thereon.

A still further object is to provide means for supporting the lamp upon the cap of 25 the user.

Other objects and advantages will be apparent from the following description, and it will be understood that changes in the specific structure shown and described may 30 be made within the scope of the claims without departing from the spirit of the invention.

In the drawings, Figure 1 is a side elevation of my improved lamp, in position for 35 use, Fig. 2 is a vertical central sectional view taken on the line 3—3 of Fig. 3, Fig. 3 is a top plan view of the device, Fig. 4 is a detail view of the supporting bracket for the burner globe, Fig. 5 is a detail view of a 40 retaining member for the top of the globe.

Referring to the drawings in which like characters denote like parts, I have shown my improved miner's lamp, which comprises the carbid reservoir 10, which as more particularly shown in Fig. 2 of the drawings 45 has a concaved inner face adapted to conform to the shape of the cap of the wearer, the outer and side faces of the reservoir being angular in cross section, said reservoir 50 having attached to its concaved inner surface, a depending pin 11 adapted for securing the device to the cap in the usual manner. The reservoir is adapted to contain the carbid in granular form and is provided 55 with a screw cap 12, through the medium of which the carbid is fed to the reservoir.

Disposed upon the upper wall of the reservoir and depending into an opening therein is a water tank 13, which is supported upon the upper wall of the reservoir as by 60 means of an annular flanged ring 14, which is secured to the tank and the reservoir and said tank is also provided with a screw cap 15 through which water may be poured into the tank. The lower end of the tank 13 is 65 slightly conical and has an extension 16 of reduced diameter and having a central bore 17 and a conical valve seat 18, said bore being opened or closed as desired by means of an operating stem 19 having a corresponding conical end adapted to be received in the seat 18 and thereby regulate the amount of water discharged from the water tank. The stem 19 extends through the outer wall of the reservoir and is provided with an 70 operating head 20.

Extending outwardly from the outer wall of the reservoir there is a suitable bracket 21 having a suitable angular brace member 22 secured thereto, the outer end of said 75 bracket being adapted to support a cylindrical base 23, said jacket having a central aperture 24 through which a burner pipe 25 is extended, said pipe being in communication with the reservoir above the operating 80 stem 19 and extending at an angle to beneath said cylindrical base and more especially the aperture therethrough. The burner pipe is adapted to convey the gas generated within the reservoir to the burner 85 and a valve 26 of the usual type is provided for regulating the flow thereof, it being understood that the carbid is poured into the reservoir through the opening therein and the water tank similarly filled with water, 90 the valve stem is then operated to allow the water to drip very slowly from the tank so a proper amount of gas will be generated and flow through the burner pipe, for all 95 useful purposes.

Supported upon the cylindrical base 23 is a burner globe 27, which is preferably of glass and adapted to be positioned at a slight distance from the reservoir, the burner being adapted to extend upwardly a 100 slight distance within the globe. To prevent the globe from becoming displaced upon the cylindrical base 23 I provide a spring keeper which comprises an arm 28, which is secured to the upper end of the water tank, the outer 105 end of said arm being bent to form a depending hanger 29 to which is secured a 110

pair of cross arms 30 having depending ends 31 adapted to engage over a collar formed upon the upper end of the globe and it will be seen that said arm will hold said globe 5 against displacement but in lighting the burner it is only necessary to raise the globe against the action of the spring, whereby a match or the like may be inserted underneath the globe.

10 From the foregoing it will be seen that I have provided a miner's lamp which can be very cheaply manufactured and one which will be very desirable for such use, inasmuch as there is small liability of the same catching fire, thereby avoiding accidents usually occurring from this cause.

What is claimed is:

1. A miner's lamp comprising a gas supply reservoir, a bracket secured adjacent the 20 bottom of the front wall of the reservoir and having a pair of openings therethrough, a burner pipe extending from the reservoir, said pipe being disposed downwardly through one of said openings and upwardly 25 through the other of said openings, a burner carried thereby, a globe supported upon said bracket and a keeper secured to the top of the reservoir and engaged with the upper end of the globe to hold the same in position.

2. A miner's lamp comprising a suitable 30 gas generating vessel, having means for securing the same to the cap of the user, a supporting bracket secured to the vessel and 35 extending outwardly therefrom, said bracket having a circular base upon its outer end

provided with an annular groove, a valve controlled burner carrying pipe in communication with the vessel and extending through the base, a globe having an enlarged upper portion and a restricted lower end seated in said groove, and means for bracing the globe at its upper end.

3. A lamp comprising a suitable generating vessel for gas, said vessel having a concaved inner surface, means secured to said surface for attaching the same to an object, a bracket secured to the lower front wall of said vessel, a cylindrical base carried by said bracket, said base having a central aperture therethrough, a burner pipe extending from said vessel and adapted to convey gas therefrom, said burner pipe extending upwardly through said aperture and provided with a suitable burner, a valve in said pipe for regulating the supply of gas, a globe supported upon said base and over the burner and a spring keeper secured to said generating vessel, said keeper comprising an arm extending outwardly from said vessel and 60 having a depending hanger formed thereon and a pair of cross arms provided with depending portions engageable over the upper end of the globe, for holding the same in a rigid position but allowing of the raising 65 thereof to permit the lighting of the burner.

In testimony whereof I affix my signature, in presence of two witnesses.

MARTIN JAMES CURTIS.
